(57) **CLAIM**

The ornamental design for origami magnetic neck wear, as shown and described.

DESCRIPTION

FIG. 1. Is a top view of origami magnetic neckwear showing my new design; and,

FIG. 2. Is the bottom view of origami magnetic neckwear thereof.

The origami magnetic neckwear is thin and of no appreciable thickness.

The dot-dot broken lines shown in the top two corners of the origami magnetic neck wear represent stitching, and form part of the claimed design.

Neck wear consisting of a fabric utilizing origami techniques folded and bound together by magnetic coupling. The claimed origami neck wear is used to enhance the neck line of men and women's attire for ornamental purposes.
